MECHANISM FOR AND METHOD OF EF-
FECTING CHANGES IN PLATING

Robert H. Lawson, Pawtucket, and Arthur N. Cloutier, Lonsdale, R. I., assignors to Hemphill Company, Central Falls, R. I., a corporation of Massachusetts

Application April 16, 1929, Serial No. 355,559
Renewed June 23, 1937

6 Claims. (Cl. 66—107)

This invention relates to mechanism for and method of effecting changes in plating.

In order that the principle of the invention may be readily understood, we have in the accompanying drawings disclosed one embodiment of means constituting said mechanism and will describe the best manner known to us for practising the method of the invention.

In said drawings:

10 Fig. 1 is a plan view of the sinker cam ring of a circular knitting machine, the cap being removed to show the three pathways for instrumentalities hereinafter referred to;

Fig. 2 is a vertical central section of the construction shown in Fig. 1;

Figs. 3, 4 and 5 represent vertical transverse sections taken through the sinker cam ring and the upper end of the needle cylinder and showing one of the needles and the sinker or web holder pertaining thereto, and also a jack preferably employed therewith, said three figures representing different stages in the loop or stitch formation for normal plating;

Figs. 6, 7 and 8 are views corresponding to Figs. 25 3, 4 and 5 but representing corresponding positions of the needle in stitch formation for reverse plating;

Fig. 9 is a perspective view on an enlarged scale of three needles and sinkers therefor employed 30 in effecting normal plating at each of said needles and for the sake of clearness representing the parts as widely laterally spaced;

Fig. 9a represents in side elevation the three needles shown in Fig. 9 with the two yarns within 35 the hooks thereof;

Fig. 10 is a view similar to Fig. 9 but representing reverse plating as occurring at each needle;

Fig. 10a represents in side elevation the three needles shown in Fig. 10 with the two yarns 40 within the hooks thereof;

Fig. 11 is a view similar to Fig. 9 but representing normal plating as occurring at the first and third needles and reverse plating as occurring at the second or middle needle; and

45 Fig. 11a represents in side elevation the three needles shown in Fig. 11 with the two yarns within the hooks thereof.

In the reissue patent to Robert H. Lawson, No. 16,584, dated April 5, 1927, there is disclosed 50 means for effecting reverse plating by the action of casting off mechanism, whereby striping extending lengthwise the hosiery or other knitted article is effected. Herein we have disclosed means for effecting reverse plating through the action of special instrumentalities, herein shown

as so-called sinkers or web holders. Herein the reverse plating is effected in lines, bands, blocks, dots or other areas which are of precisely the intended width. That is to say, by the mechanism and method of our invention, we are able to make 5 reverse plating of precisely a single needle or needle wale in width, whereas heretofore it has been exceedingly difficult to make reverse plating lines or areas of a single needle or single needle wale in width. We are also able to make reverse 10 plating areas of any precise number of needle wales that are desired. In the present invention, we employ a special instrumentality for each needle so that the entire series of needles has associated therewith a corresponding number of 15 sinkers.

We have shown the invention as applied to a circular knitting machine of independent needle type, such, for example, as a Banner machine of the general form disclosed in U. S. patent to 20 Joshua D. Hemphill, No. 933,443. The needles are desirably latch needles and are preferably operated in usual manner, and two yarns are fed thereto in plating relation, preferably as shown in the said Reissue Patent No. 16,584, and 25 the tension is applied desirably to the same thread or yarn as is disclosed in the said reissue patent, and the other yarn or thread is fed either without tension or with a markedly less tension. Although our invention is not limited to the application of tension to the yarn or thread disclosed as the tensioned one in said reissue patent, we 30 preferably so apply the tension that the white yarn (indicated in Figs. 3 and 6 as the lower yarn in the hook of the needle) is the tensioned 35 yarn, and the upper or black yarn being fed without tension or markedly less tension.

Referring first to Figs. 1 to 8, the needle cylinder is indicated at 1 and the sinker cam ring bed is indicated at 2. The needles 3 are located for 40 usual sliding movement in the grooves 4. The sinker cam bed is provided with usual radial grooves in each of which is a single sinker only, as indicated at 5 in the several figures. Beneath each sinker in the same groove therewith is located a jack 6 having lengthwise sliding movement independent of that of the sinker.

As shown most clearly in Fig. 1, the sinker cam ring is provided with three pathways, namely, the outer pathway 7 in which travel only the butts 50 8 of the jacks 6, the intermediate pathway 9 and the innermost pathway 10. The butts 8 of the jacks 6 travel either in the pathway 7 or the pathway 9 according to the control of the said jacks in a manner similar to the control of the 55

so-called diagonal or dial or jacquard Banner machines by which instrumentalities in the nature of jacks act according to the desired pattern to leave the instrumentalities in an outer pathway or to advance the same to an inner pathway.

In the present mechanism at the point 10 shown in Fig. 1, or at the point diametrically opposite thereto, means in the nature of sliding jacks act upon the predetermined butts 8 of desired jacks 6 to move them slightly inward, so that they will travel in the intermediate pathway 9. Jacks 6, which are not so acted upon by said other sliding jacks, are left to travel in the outer pathway 1. A type of means for effecting the selection of instrumentalities by sliding jacks is disclosed in the pending application of Lawson and Lawson, Serial No. 145,512, filed November 1, 1926, Patent 1,897,130.

Any suitable pattern means may be provided 20 to direct desired jacks 6 into the intermediate pathway; such pattern means would act in accordance with the predetermined pattern so that only at the needles whose jacks 6 are guided or moved into the intermediate pathway 9 is reverse 25 plating effected, normal plating occurring upon all the other needles.

As shown most clearly in Fig. 1, the inner pathway 10 is relatively wide in a direction radial to the needle cylinder, at 11, which is bounded at 30 the inner side by a part of the cam 12 and at the outer side by the cam end 13 of the almost completely circumferential guiding formation 14. The guiding edge 15 of the cam 12 is succeeded in a contraclockwise direction by the sharply outwardly sloping edge 16 terminating at a point 17 beyond which in a contraclockwise direction is the inwardly sloping edge 18. We have indicated the knitting point at 19 and the casting off point at 20. The inner edge of the cam end 40 13 is slightly curved as indicated at 21 and extends inward to a point 22 circumferentially beyond which, as indicated at 23, the formation 14 slopes outwardly, being succeeded by a concentric edge extending about the greater part of the series 45 of sinkers.

In Figs. 3, 4 and 5 are shown the positions of the sinkers 5 and jacks 6 during normal plating, and it will be evident that the shoulder 24 which is provided upon each jack 6 in advance of its 50 butt 8 never comes in normal plating in contact with the outer end 25 of the stem or tail portion of its sinker 5. Each sinker is provided with a butt 26 which during normal plating is against the outer edge of the pathway 11 and hence each 55 sinker is in its outermost position as determined by the guiding edge of the pathway at that point. Therefore, normal plating occurs upon each sinker unless it is moved inwardly at some point by engagement of the shoulder 24 of the jack 6 with the end 25 of the corresponding sinker 5. During normal plating the butt 8 of every jack 9 is in the outer pathway 1.

An inspection of Figs. 6, 7 and 8 showing the 60 position of the parts for reverse plating discloses that the butt 8 of the jack 6 for reverse plating has been brought into the intermediate pathway 9. Therefore, at a suitable point, the shoulder 24 of that jack contacts with the end 70 25 of the corresponding sinker 5 and gives the said sinker a slight inward movement that would not be imparted by the outer guiding edge of the inner pathway 11. This is evident from an inspection of Fig. 6, and a comparison of that figure 75 with Fig. 3 discloses that the sinker 5 for reverse

plating occupies a position further in radially than does the same sinker at the same location when normal plating is to occur thereon.

Each of the sinkers 5 of the entire series is shaped as shown in Figs. 3 to 8 inclusive. Each 5 is of the full width of its sinker groove and rests upon its jack 6 which is also of the full width of that groove. Each sinker is provided with the lower nib 27 which may be of usual construction, and above the same and suitably spaced therefrom it is provided with a nib 28. The upper edge 29 of said nib 28 slopes upwardly as indicated, to a point 30, and outwardly beyond the point 30 is a narrow downwardly extending throat 31 above which is the upper nib 32, the extreme top 15 of which upper nib slopes downwardly and outwardly as indicated at 33, and below the nib 32 is a downwardly and outwardly sloping and preferably concaved guiding edge 34.

The two yarns indicated at T and NT respectively are introduced in a plating relation preferably in the manner disclosed in the said reissue patent to Lawson, No. 16,584, the lower yarn, shown as white, being the tensioned yarn and the upper yarn shown as black, being the non-tensioned yarn. The front incline 29 of the sinker 5 insures the pressing of the tensioned yarn T inwardly against the needle shank 3 so as to insure the continuation of normal plating up to the very needle wale where reverse plating 30 is desired. The inclined throat 31 sloping down, as shown, is provided mainly to get the stitches back down to the level which the incipient stitches had when at the front or inner end of the slope 29 of the sinker 5; that is, to get the top 35 of the loops back down to the normal lower knitting level, at which the loops would have been if the sloping edge 29 were not provided but had been level or flat instead of wedge shaped.

In normal plating the loops remain below or in 40 front of the upper nibs 33 as is evident from Figs. 3, 4 and 5, and also from Fig. 9; but in reverse plating the loops of both threads pass onto the top of the nib 32 and down the back edge of the same and the back edge of the sinker, as 45 is evident from an inspection of Figs. 6, 7 and 8 and of Fig. 10.

The purpose of the invention is to obtain reverse plating at the precise desired needle wale or wales, to make (if desired) a reverse plating 50 stripe, a single needle wale only in width, and instantly to return to normal plating; that is, in accordance with the invention we have provided means whereby the reverse plating areas are precisely determined or limited or outlined. In a co-pending application filed by Lawson and Lawson, Serial No. 172,331, filed March 3, 1927, there is disclosed a jack having a nib generally like the nib 32 and by which reverse plating is secured, but in the construction shown in that application 60 the reverse plating is of a two needle width because means are not provided to restrict the same to a single needle wale. In other words, according to said prior application, following reverse plating the two yarns are left to return to normal 65 plating because of their natural tendency to do so, and it requires the width of the next succeeding needle wale to accomplish this or permit it to result. In the present invention, however, the reverse plating may be of a single needle width or 70 wale only, and the yarns are compelled to return to normal plating for the very next needle wale. Of course, the reverse plating areas may be of any desired number of needles or wales in width, but whatever the width, normal plating is permitted 75

to begin only upon the precise desired needle wale and is compelled to end upon the precise desired needle wale, whether such reverse plating be one needle wale in width or more than one needle wale in width.

It is obvious from an inspection of Figs. 6, 7, 8 that not only are the two threads reversed in position so that they move down the downwardly, outwardly inclined edge 34, but that the stitch is 10 cast off at the lower part of said inclined edge.

Referring to Figs. 9 to 11 inclusive, we have shown in said figures perspective, three successive needles and their sinkers. In Fig. 9, the needles are indicated at A, B and C respectively, and 15 are accorded the same designation in Fig. 9a.

In Figs. 9 and 9a, it is to be understood that normal plating only occurs, and it is to be also understood that the knitting point is about one and a half to two needles further to the left viewing Fig. 9 than is the needle C.

In Fig. 10, wherein reverse plating only occurs, the three needles are designated A', B', C', and obviously they may be the same identical needles indicated at A, B, C in Fig. 9 in subsequent courses 25 of the work, or they may be another group of three needles. The said needles A', B', C' are similarly designated in Fig. 10a.

In Fig. 11 there are designated three needles A, B', C, and it is to be understood that normal plating occurs upon the needle A, that reverse plating occurs upon the needle B', and that normal plating occurs upon the needle C. Said needles are similarly designated in Fig. 11a.

In the present disclosure, and referring to a needle at which reverse plating is to occur, we do not turn or change from normal plating to reverse plating by the sinker on the side of the needle which is nearest the knitting point, but we turn the yarns only by the sinker on the other 40 side of the needle, namely, the side furthest from the knitting point. Thus we obtain a one needle line of reverse plating or exact line of reverse plating of any desired width. This is effected because the two yarns are bound at the side of the sinker in question, nearest the knitting point.

45 The binding occurs between the hook of the needle and the inclined edge 29 of the sinker thereof whereat normal plating is returned to. That is to say, if reverse plating is to occur only on the needle B' (Fig. 11) the binding will occur between the needle C and its own sinker 5 at the inclined edge 29 thereof. Reverse plating is effected at the inclined edge 34 of the sinker of the needle B' and occurs at the near side of that edge viewing the sinker of the needle B' in Fig. 11. As indicated in Fig. 11, the yarns are knitted by the needle C in a normal plating relation and the yarns are knitted by the adjacent needle B' in a reverse plated relation, thus the normal plating by the needle C is not disturbed by the reverse plating in the stitches knitted by the needles B' which follows (in the knitting cycle) the needle C in a process of knitting. This action 55 occurs whatever the width of the reverse plating stripe or area whether the width be one needle wale or a plurality of needle wales, and a similar binding action occurs at the needle and its sinker just anterior to the needle whereat reverse plating is to begin or whereon it is to occur if it be upon a single needle only. Heretofore when reverse plating has been attempted by a sinker or instrumentality on a single needle only, it has been attempted only on the side nearest the knitting point (with respect to that needle). In ac-

cordance with our invention, we reverse only on the side away from the knitting point.

The hump defined by the point 30 on each sinker raises the edge of the sinker over which the yarns are drawn as by the needle C, Fig. 11, 5 which hump thus acts upon the yarns by engaging them before reversal of the yarns in the hook of the needle B' by the adjacent sinker (intermediate sinker, Fig. 11) can effect reversal of the yarns in the hook of the needle C. 10

Summarizing the preceding description: reverse plating is effected at a needle wale by causing yarns to be drawn over the downwardly and outwardly inclined edge of a sinker as by the needle B' over the intermediate sinker of 15 Fig. 11, and normal plating is effected by causing a needle such as the needle C, Fig. 11, drawing yarns over the downwardly and inwardly inclined edge 29. The outwardly and downwardly inclined edge on the intermediate sinker, Fig. 11, 20 causes the yarn to ride up the bill side of the hook whereas the downwardly and inwardly inclined edge 29 causes the yarns to ride up the shank side of the hook of the needle C, as a consequence of which the yarns are relatively 25 reversed in position in their respective needle hooks. The raised edge provided by the incline 29, serves the additional function of engaging the yarns and binding them in cooperation with the hook of the needle as the needle C before they would 30 otherwise be engaged and bound if the hump were not present in which case the reversal of the yarns by the needle B' drawing the yarns over the outwardly and downwardly inclined edge of the intermediate sinker would cause the yarns 35 likewise to reverse in the hook of the needle C.

It is to be understood that the stitch or loop is not loosened at the wale or wales where reverse plating occurs. There is no perceptible looseness of the stitches or loops in the wale or wales where- 40 in reverse plating occurs in accordance with our invention.

In Fig. 9a we have indicated at the needle B the upper edge of the nib 28 of the sinker 5, thus indicating the sloping or wedging edge 29 and the downwardly sloping throat 31, and in Figs. 10a and 11a at the needle B' we have indicated the back sloping edge of the sinker at 34.

Having thus described certain illustrative embodiments of the invention, it is to be understood that although specific terms are employed, they are used in a generic and descriptive sense, and not for purposes of limitation, the scope of the invention being set forth in the following claims.

We claim:

1. In a knitting machine of the independent needles type, a series of needles, means for feeding two yarns thereto in a plating relation, a sinker like special instrumentality for each needle movable transversely of the needle series, and having an edge formation cooperating in effecting reverse plating, a jack located in the same groove as and beneath each instrumentality, and means to move said jacks thereby to move the desired instrumentalities to cause the edge formations thereof to co-act in effecting reverse plating, in combination with means for controlling the needles and special instrumentalities to effect the knitting of normal plating.

2. In a knitting machine of the independent 70 needle type, a series of needles, means for feeding two yarns thereto in a plating relation, a sinker like special instrumentality for each needle movable transversely of the needle series, said instrumentalities and needles acting to bind the

threads so that reverse plating occurs only at the actual needle or needles whose instrumentalities are moved transversely a distance in excess of the normal movement required for normal plating, each of said instrumentalities having at its forward part a binding edge for the threads and having a top nib, over the top and down back of which at least one of the threads passes in reverse plating, and a jack for each such instrumentation, and means to move said jacks so as thereby to move desired instrumentalities in effecting reverse plating.

3. A method of knitting plated areas including feeding two yarns to the needles of a knitting machine in a plating relation and effecting the knitting of stitches, causing instrumentalities cooperating with the needles to effect a reversal of the yarns at one or more of the wales knitted by the said needles, and causing an adjacent instrumentation next in advance of a needle whereat reversal of the yarns is not to occur, to act upon the yarns by engaging them before reversal of the yarns by the adjacent instrumentation in the direction of yarn supply can effect reversal of the yarns at the said needle whereat reversal of the yarns is not to occur.

4. In a knitting machine of the independent needle type, a series of needles, means for feeding two yarns thereto in a plating relation, a sinker like special instrumentation for each needle movable transversely of the needle series, whereby normal plating occurs upon the needles whose said instrumentalities are moved transversely a normal distance and reverse plating occurs upon the needles whose said instrumentalities are moved transversely a greater distance, said instrumentalities having reverse-plating restricting formations to engage the yarn or yarns each of some of the said instrumentalities being so arranged and controlled that one of the said instrumentalities immediately in advance of an-

other instrumentality acts upon the yarns to prevent reverse plating effected by the last mentioned instrumentality from causing reverse plating to be effected at the wale knitted by a needle located between the said last mentioned instrumentation and the instrumentality in advance thereof.

5. A knitting machine having independent needles and cooperating instrumentalities for effecting the knitting of plated stitches, the instrumentalities being constructed to effect normal plating at some wales and reverse plating at other wales, the construction and operation of the said instrumentalities being such that reverse plating is effected at a wale where the plating relations of the threads are governed by one of the said instrumentalities and, at a wale knitted immediately prior to the knitting of the wale first mentioned, a second instrumentation having a relatively raised portion engages the yarns and thereby prevents the reverse plating effected by the first mentioned instrumentation extending beyond the wale effected in the direction of the second mentioned instrumentation.

6. A method of knitting plated areas including feeding two yarns to the needles of a knitting machine in a plating relation and effecting the knitting of stitches, causing instrumentalities cooperating with the needles to effect a reversal of the yarns at one or more of the wales knitted by the said needles, and causing an adjacent instrumentation next in advance of a needle whereat reversal of the yarns is not to occur, to act upon the yarns before reversal of the yarns by the adjacent instrumentation in the direction of yarn supply can effect reversal of the yarns at the said needle whereat reversal of the yarns is not to occur.

ROBERT H. LAWSON.
ARTHUR N. CLOUTIER.
